US0D1104962S

(12) **United States Design Patent** (10) Patent No.: **US D1,104,962 S**
(45) Date of Patent: ** Dec. 9, 2025

(54) **POWER BLOCK**

(71) Applicant: **ChargePoint, Inc.**, Campbell, CA (US)

(72) Inventors: **Justin D. Cumming**, Winthrop, ME (US); **Peter H. Muller**, Portland, OR (US); **David Hoenig**, Los Gatos, CA (US); **Pasquale Romano**, Los Gatos, CA (US); **Paul J. Andrus**, San Jose, CA (US); **Stephen Eric Sidle**, Morgan Hill, CA (US)

(73) Assignee: **CHARGEPOINT, INC.**, Campbell, CA (US)

(**) Term: **15 Years**

(21) Appl. No.: **29/825,365**

(22) Filed: **Jan. 31, 2022**

(51) LOC (15) Cl. **13-02**

(52) U.S. Cl.

USPC **D13/107**; D13/110

(57) **CLAIM**

The ornamental design for a power block as shown and described.

DESCRIPTION

FIG. 1 shows a front perspective view of a power block showing the claimed design;

FIG. 2 shows a front view thereof;

FIG. 3 shows a back view thereof;

FIG. 4 shows a right view thereof;

FIG. 5 shows a left view thereof;

FIG. 6 shows a top view thereof;

FIG. 7 shows a bottom view thereof; and,

FIG. 8 shows a rear perspective view thereof.

The broken lines illustrate environmental structure and/or portions of the power block that form no part of the claimed design.

1 Claim, 8 Drawing Sheets
